UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR-SEAT.

1,178,285.

Specification of Letters Patent.

Patented Apr. 4, 1916.

Application filed November 24, 1913. Serial No. 802,703.

To all whom it may concern:

Be it known that I, WALTER S. ADAMS, a citizen of the United States, residing in Philadelphia, Pennsylvania, have invented 5 certain Improvements in Car-Seats, of which the following is a specification.

The object of this invention is to make a car seat structure in such a manner that the shifting seat section and the movable back 10 section are so connected together that both can be bodily removed from the supports when the back is turned to a central position, but when the back is moved either to one side or to the other then the seat section 15 and the back are locked to the supports so that they cannot be accidentally displaced.

The invention also relates to certain details which will be fully described hereinafter, reference being had to the accompanying 20 drawings, in which:

Figure 1 is an end view of the car seat showing the back in one of its two normal positions at one side of the seat section; Fig. 2 is a side view; Fig. 3 is a detached 25 perspective view, showing the seat and the back section lifted off of the supports; Fig. 4 is a perspective view of the seat supports; Fig. 5 is an end view of the car seat, showing the back in the mid position so that 30 the seat and the back can be removed from the seat supports; Fig. 6 is a detached view of the wall bracket; Fig. 7 is a view of the upper portion of the pedestal support; Fig. 8 is a detached perspective view of the 35 end of the seat cushion; Fig. 9 is a view of the bracket of the back section; Fig. 10 is a detached view of one of the arms; and Figs. 11 and 12 are diagrams illustrating the pins in different positions.

40 Heretofore, the back section was hinged to the frame of the seat structure and the seat section was removable from the mechanism and from the back so that it could be lifted off of the supports in order that access 45 could be had to the space under the seat, but the back section and the mechanism remained. This did not give an entire clear space for cleaning or repairs. In the event of a repair to the operating mechanism, the 50 car would have to be transferred to the shop and, consequently, was out of commission until the repair was made. In the construction shown, in the event of repairs being required, the seat section and the back section 55 can be removed and a duplicate section

placed in position so that the car is always in commission. This is an important feature.

By coupling the seat proper, or cushion, and the back together there is no liability 60 of the mechanism becoming disarranged.

In the present instance, 1 is the side of a car on which is secured a bracket 2 having curved seat supports 3.

4 is an aisle pedestal having a curved seat 65 support 5, curved similarly to the seat support 3, and projecting from each seat support is an extension 6 having a T-slot 15 therein for the reception of the pivots attached to the seat section 7. This seat section has curved ribs or rockers 8 resting on the curved seat supports so that when the seat section is moved to either side it will slide on these curved seat supports and will assume a slight angle, as in Fig. 1, with the 70 front of the seat raised a greater distance from the floor than the back thereof.

9 is the back section made in the usual form and having brackets 16 secured at each edge. Each of these brackets has a central 80 pivot pin 13 and on each side of this central pivot pin are two pivot pins 17.

10, 10 are two parallel links pivoted to the pins 17, 17 respectively and to the pins 18, 18 respectively on the seat section so that the back, as it is shifted from one side to the other, will assume a proper angle with respect to the seat section. A shaft 12 extends under the seat section and has its bearings in the rockers 8 and end plate 8^a and is located between the pivot pins 18.

11, 11 are two flat arms, one located on each side of the seat structure. One end of each arm is secured to the shaft 12 and the other end is mounted on the pivot pin 13 95 on the bracket 16 of the back section. This plate may be held in position by one or two screws at the pivot points 13 or 12, as desired. Other means of fastening may be employed, if desired. In the present instance the plates 11 are broad and flat so as to overlap the two parallel links 10 and these links may be shaped in any manner desired to make the connection more or less ornamental. The flat arms 11 retain the 100 links in position on their pivot pins without other fastenings, as shown in the drawings.

The ends of the shaft 12 project beyond the arms 11 and extend into the T-slot 15 in each support and projecting from the arm 110

11, at the wall end of the seat, is a pin 14, which is located a given distance from the shaft 12 and near the aisle end is an arm 11^a which is secured to the shaft 12 and extending under the seat section. This arm 11^a has a pin 14^a in line with the pin 14. These two pins 14 and 14^a are located in the narrow vertical portions 20 of the T-slots 15 in the bracket and pedestal, while the projecting portions of the shaft 12 are located in the transverse portions 21 of the T-slots 15. When the back is in either of its two normal positions, as in Fig. 1, then the ends of the shaft 12 are under the overhanging portion 19, Fig. 11, so that it will be impossible to lift the seat sections off of their supports. Furthermore, the outer edge of the seat section is locked to the support, which prevents it from being lifted when a person occupying the seat rises suddenly therefrom. In light seat structures, such as those used in trolley cars, this is annoying, yet it often occurs if the seat is not firmly secured to its supports.

25 When the back is moved to the central position, as shown in Fig. 5, then the shaft 12 will be in line with the pins 14 and 14^a and also in line with the portion 20 of the T-slot, as in Fig. 12, so that the entire structure can be raised clear of the supports and removed. The moment, however, the back is moved either to the right or to the left, the pins 14, 14^a, act as pivots and the ends of the shaft 12 pass into the transverse slot 21 35 out of line with the vertical slot 20, locking the seat structure to its supports.

While I have shown a bracket at the wall end of the car, a pedestal may be used at this end, as well as at the aisle end, and 40 while the invention is particularly adapted for a car seat, it can be used as a seat structure for other purposes where it is desired to make a shifting seat and one which can be bodily removed from its supports.

45 In the specification, I have used the term "seat section" meaning the seat proper, or cushion, and not the independent frame which usually supports the cushion.

By the above construction, it will be seen 50 that I permanently connect the seat proper, or cushion, to the movable back directly by arms, or links and arms, so that the back can be shifted to either side of the seat.

When it is desired to remove the cushion, 55 or seat proper, from the supporting frame, the back and seat are removed as a unit, leaving, in the present instance, the wall bracket and pedestal as the permanent structure so that access can be had to all parts of the car 60 floor.

I claim:

1. The combination of a seat cushion having a back pivoted thereto so that it can be shifted to either side thereof; with a permanent support upon which the seat cushion

directly rests and from which it is removable with the back.

2. The combination in a car seat, of a fixed base having bearings; a seat cushion removably mounted in the bearings; a back section; and links permanently connecting the seat cushion to the back section so that the seat cushion and back can be removed from the bearing as a unitary structure.

3. In a car seat structure, the combination 75 of a permanent seat support; a seat cushion mounted directly on the seat support; a back; permanent connections between the seat cushion and the back; and means engaging the fixed support so that, when the back 80 is shifted from one side of the seat to the other, it will move the cushion in the opposite direction.

4. The combination in a car seat, of fixed 85 bearings secured to the car body and each having a seat support; a seat cushion and back section permanently connected by links; a pivot shaft carried by the seat cushion and arranged to enter slots in the bearings, the seat resting on the seat supports so that the 90 seat cushion and back section can be removed from the bearings as a unit.

5. The combination in a car seat structure, 95 of a pedestal and bracket, each having a seat support; a seat cushion resting directly upon the seat support and arranged to be detached bodily therefrom; a back section; links connecting the back section with the seat cushion; and means engaging the bracket and pedestal so that the seat cushion 100 will be shifted when the back is turned from one side to the other.

6. The combination of a slotted seat support secured to a car body; a seat section and a back section; links connecting the two 105 so that the back section can be moved to either side of the seat; a pivot shaft on the seat section extending into the slots on the seat support arms secured to the shaft and pins connected to the shaft also extending 110 into the slots in the seat supports so that the seat cushion will be shifted when the back is turned and when it is desired to remove the structure the seat cushion, back and connecting arm, and links are removed 115 as a unit.

7. The combination in a car seat, of a back; a shaft mounted in bearings on the seat and extending beyond the end thereof; parallel links pivoted to the back and to the seat; a flat arm secured to each end of the shaft and pivoted to the back, said arms being of a greater width than the combined width of the links, whereby the links are retained on their pivots by the arms without other fastenings.

8. The combination in a car seat, of a movable seat cushion; a back section; parallel links connecting the back section to the seat cushion; a longitudinal shaft mounted 130

on the under side of the seat cushion; arms 5 on the shaft pivotally connected to the back section; curved seat supports on which the seat cushion rests and having slotted extensions for the reception of the shaft; pins 10 carried by the shaft, also extending into the said slots so that when the back section is turned the seat cushion will slide on its supports and when the back section is in the central position the seat cushion, back 15 and connecting members can be lifted off of the supports as a unit.

9. In a car seat structure, the combination 20 of permanent supports, each support having a centrally located T-slot therein; a seat cushion mounted directly on the supports; a longitudinal shaft mounted in bearings on the cushion and extending into the T-slot of each permanent support; a movable 25 back section; a pair of links connecting the back section directly to the seat cushion; arms secured to the shaft and pivotally connected to the back, one of said arms having a pin adapted to engage the T-slot in one support; an arm on the shaft 30 having a pin adapted to engage the slot of the other support so that when the back is moved to either side of the seat cushion, the cushion will be shifted in the opposite direction and when the back is in the central 35 position the cushion, back, and connecting members can be removed as a unit from the seat supports.

10. The combination in a car seat structure, of fixed supports, each having a seat cushion support and a centrally located T-slot; a seat cushion mounted directly on the seat supports; an end plate rigidly secured to the seat cushion and having bearings 40 therein; a longitudinal shaft mounted in the bearings and projecting into the T-slot in the supports; a movable back section; links connecting the back section to the plates which are secured to the seat cushion-

ion; arms secured to the shaft and pivoted 45 to the back section and overlapping the links, one of said arms having a pin also entering the T-slot; an arm on the shaft having a pin entering the other T-slot, the parts being so arranged that, when the back 50 is turned from one side to the other, the seat will move in the opposite direction and when the back is located in the central position it can be removed with the seat cushion and the connecting members as a unit. 55

11. The combination in a car seat structure, of a wall bracket and a pedestal each having a seat cushion support and an upright extension with a T-slot therein; a seat cushion having rockers permanently attached thereto and resting on the seat supports, the cushion extending beyond the pedestal at the aisle end of the seat; a plate secured to the aisle end of the seat cushion; a longitudinal shaft extending 60 through the two rockers and the plate; a movable back section; two links at each side of the seat structure connecting the back section to the seat cushion; an arm on each side of the seat structure secured to 65 the shaft and pivotally connected to the back; a longitudinal shaft extending into the T-slots of the wall bracket and pedestal; a pin on one of the arms extending into the slot in the arm of the pedestal so that the 70 sections are locked to the pedestal when the back is in either of its extreme positions but the structure, as a unit, can be removed from the pedestal and bracket when the back section is in the mid position. 75

In testimony whereof, I have signed my name to this specification, in the presence of two subscribing witnesses.

WALTER S. ADAMS.
